UNITED STATES PATENT OFFICE.

GIANNI BETTINI, OF PARIS, FRANCE.

SPINNING DEVICE.

1,036,425.

Specification of Letters Patent. Patented Aug. 20, 1912.

Application filed January 6, 1911. Serial No. 601,147.

To all whom it may concern:

Be it known that I, GIANNI BETTINI, of Paris, France, have invented a new and useful Improvement in Spinning Devices, 5 of which the following is a full, true, and exact description, reference being had to the accompanying drawings.

This invention comprehends certain improvements on the device for which I have 10 made application for Letters Patent of the United States on or about August 31, 1910, Serial No. 579,921.

A structural embodiment of the invention is illustrated in the accompanying drawing, 15 whereof—

Figure 1 is a side elevation, with parts in section, of the improved device; Fig. 2 is a cross section through the same; Fig. 3 is a cross section of a modified form of traveler; and Fig. 4 is a perspective view of the 20 guide ring, this ring being omitted in Fig. 2.

The traveler carrier is here shown as in the form of a rectangular frame A, A, the lower member of which is provided with a 25 central ring m, and the upper member with a correspondingly-located bearing b. The spindle passes loosely through the ring m and carries a fixed collar h, between which parts is interposed a spring q designed to 30 exert its pressure downward upon said ring. At its upper end, said spindle is provided with a bearing n shaped for engagement with bearing b. The usual bobbin is carried by the spindle and is fixed to the same 35 in any preferred manner. The rail D is formed with an opening E through which the carrier extends.

The traveler or thread guide f may be of 40 many forms, one of which is shown in Fig. 2, and another in Fig. 3. In its first-mentioned form, it comprises an open wire frame of sufficient diameter to surround the bobbin when full, which frame is designed to travel upon the carrier, being provided 45 for that purpose with small sleeves r slideable upon the carrier sides. Its vertical position is controlled by arms or projections z connected to said sleeves and projecting between rail D and the guide ring T which 50 latter they are adapted to engage from beneath, said guide ring T being attached to

the rail D by the screw e and being also provided with lugs k which rest upon said rail. The spindle is driven in the usual manner through the medium of a pulley l, 55 or the like, and, in rotating, has a tendency to rotate the carrier, owing to the frictional contact between the two. Hence, the traveler is capable not only of vertical motion, which is controlled by ring D, but also of 60 a rotary motion around the spindle.

In the modification shown in Fig. 3, the traveler is pivotally mounted adjacent its outer end on the carrier, and is designed to bear intermediate its ends against the bobbin, being preferably provided at its said outer end with a small air-wing c, or similar device, which assists in maintaining it 65 in the position specified.

I claim as my invention:

1. The combination, with a rectangular carrier frame having its top member provided with a central bearing and its bottom member with a central ring; of a spindle passed loosely through said ring and provided at 70 its upper end with a bearing removably engaged with the first-named bearing; means for rotating the spindle; a bobbin secured to said spindle; a collar secured to said spindle in juxtaposition to said ring; and a spring interposed between said collar and ring and bearing against the latter, for rotating said carrier frame when said spindle is rotated.

2. The combination, with a spindle, means 75 for rotating the same and a bobbin secured to said spindle; of a carrier frame mounted upon the spindle; connections between said spindle and said frame, for rotating the latter from the former; a rail provided with an 80 opening through which said carrier frame extends; a guide ring mounted upon said rail and secured thereto; and a vertically movable traveler mounted on said carrier frame above the guide ring and provided with a 85 controlling member disposed between said guide ring and rail and adapted for engagement with the former from beneath.

GIANNI BETTINI.
